UNITED STATES PATENT OFFICE.

CHARLES CASH AND NICHOLAS E. WILSON, OF JOHNSON CITY, TENNESSEE.

WHISTLE.

Application filed March 7, 1925. Serial No. 13,845.

This invention relates to whistles and more particularly to the construction of a locomotive whistle.

An important object of the invention is to provide a whistle which may be arranged to have a distinctive note or collection of notes so that it may be readily recognized. It is well known that engineers particularly of locomotives like to have a whistle attached to their engine which is clearly distinctive and which will be readily recognized by persons hearing the same.

A still further object of the invention is to provide a whistle construction such that the note or combination of notes produced by the whistle may be altered at will and in which the arrangement permitting such changing of the whistle note is simply and readily operated.

A still further object of the invention is to provide a device of this character which may be relatively cheaply produced and installed and which, as a matter of fact, may be substituted for the ordinary whistle bell now employed on the whistles of locomotives.

These and other objects we attain by the construction shown in the accompanying drawings, wherein for the purpose of illustration is shown a preferred embodiment of our invention and wherein:—

Figure 1 is a side elevation of a whistle constructed in accordance with our invention;

Figure 2 is a bottom plan view of the whistle bell;

Figure 3 is a transverse sectional view through the bell and its support;

Figure 4 is a vertical sectional view through the whistle;

Figure 5 is a plan view of the note;

Figure 6 is a vertical sectional view through a slightly modified form in which the structure is produced by casting, the pistons being removed;

Figure 7 is a transverse sectional view through the form of whistle bell shown in Figure 6;

Figure 8 is a vertical sectional view showing a modified manner of obtaining the adjustment of the piston; and

Figure 9 is a section on the line 9—9 of Figure 8.

Referring now more particularly to the drawings, that form of construction shown in Figures 1 to 5 the numeral 10 designates

a standard whistle base which, as is well known to those familiar with the art, includes an outer shell 11, a spider support 12 arranged within the shell, a disk 13 supported by the spider and having its periphery extended into proximity to the inner periphery of the shell but spaced therefrom to provide a steam exhaust slot 14 and a flange 15 controlling the passage of steam to and through the slot. The spider 12 has a central threaded bore 16 for the reception of a vertical post 17 from which the bell of the whistle is supported. Upon this post at the threaded lower end 18 thereof a nut 19 is mounted for the purpose of securing the disk 13 in position and preventing movement of the post. This structure forms a normal part of the whistle structure and does not enter into the invention except as hereinafter described.

In accordance with our invention, we provide a body having a central bore 20 through which the post 17 extends. In the form of invention now under discussion, this bore is formed by providing a central tube 21. The nut 19 has between faucets thereof rounded portions 22 fitting the lower inner end of the tube to hold the same concentrically with the post 17. The upper end of this tube 21 has a cap 23, the side edges of which project to provide a flange 24, the purpose of which will presently appear. This cap has a central opening 25 through which the threaded upper end 26 of the post may extend. Upon the post 17 is mounted a round nut 28 fitting the interior of the tube and abutting the under surface of the cap. Above the upper surface of the cap, the post has mounted thereon an ornamental lock nut 29 for securing the cap in position against the nut 28. By adjusting the nut 28 vertically upon the post 17, the position of this central tube and all parts carried thereby, hereinafter to be more fully described, may be adjusted.

Surrounding the tube 21 are a plurality of whistle tubes or bells 30. These being similar, the description of one will herein suffice. Each tube has a closed upper end 31 having extending upwardly therefrom a tubular stem guide 32, the upper end of which is split, as at 33, and the exterior of which is tapered and exteriorly screw-threaded, as at 34. Coacting with this stem guide is a locking band 35 which, when screwed down upon the guide, will compress

the upper end thereof to bind the same against the stem 36 of a piston 37 operating within the tube and fitting the same. The upper end of this rod has a handle 38 in the form of an ornamental cap by means of which it may be adjusted. When a proper adjustment of the piston 37 is had, it may be locked in position by tightening the ring 35 so that the guide clamps against the rod 36. The piston 37 is preferably provided with a packing ring 38^a as illustrated.

In its formation, the lower end of each tube is split and the ends thereof spread, as indicated at 39. The separated tube sections 15 of adjacent tubes are secured to one another as by welding or brazing at 40 and provide radially extending baffles 41 occupying the points below the space between adjacent tubes. These baffles serve to prevent steam 20 passing from the slot 14 from spreading out and concentrate it upon the lower ends of the tubes. The tubes 30 may be secured to the tube 31 by spot welding, as indicated at 42, and may have their upper end walls 25 secured to the projecting flange 24 of the top 23 of the tube 21. In the use of this form of the device, the bell formed by the combination of tubes is placed in position upon the whistle base and the pistons 37 30 adjusted until a desired tone is produced after which they are locked in position. If it is desired to change the pitch of the tone, the entire assembly is vertically adjusted by vertically adjusting the nut 28 as hereinbefore suggested.

In the form shown in Figures 6 to 7 the same structure is produced but is produced integrally by a casting from any moldable metal. At the same time, certain changes 40 are made in the adjustments provided as will hereinafter become obvious. The wall of the bore 20 is provided at its lower end with interior threads, indicated at 43. The nut 19 is replaced by a nut 44 having a 45 depending sleeve 45 interiorly fitting and threaded into the bore 20, the lower end of this sleeve abutting the plate 13 to hold the same in position. The post employed is substantially the same with the exception of 50 the fact that the nut 28 is not employed thereon, the post extending through an opening 45 of the upper end wall 46 of the structure. The lock nut 29 is provided and an adjustment of this type, as a whole, is had by loosening this lock nut and then bodily rotating the bell until the desired 55 height of adjustment is had after which the lock nut 29 is firmly seated against the upper end of the bell.

If desired, the manner of adjusting the pistons 37 may be modified as suggested in Figures 8 and 9. In these figures, we have shown the cylinder 30 as provided with a 60 longitudinally extending groove 50 in the walls thereof and the piston 37 as provided

with a lug 51 engaging in this groove to prevent rotation of the piston. The stem of the piston, indicated at 36^a is threaded through the piston so that by rotation of this stem, the piston may be adjusted longitudinally of the cylinder. Any suitable means may be provided for locking the stem against rotation. In the present illustration, this means consists of the guide 32 and locking element 35 hereinbefore described. 70

It will be obvious that this structure as hereinbefore set forth is capable of a considerable range of change and modification without materially departing from the spirit of our invention and we accordingly do not limit ourselves to such specific structure except as hereinafter claimed. 75

We claim:—

1. In a whistle, a whistle base, a standard extending upwardly therefrom, a bell vertically adjustable upon the standard and including a plurality of tubes, means for adjustably regulating the effective length of each of said tubes, including pistons movable within each tube and having stems projecting through guides carried by the tube, said guides being compressible and means for compressing the guides to bind the same against the stems of the pistons. 85

2. In a whistle, a bell tube having one end open and the opposite end closed and provided with a tubular guiding boss, a piston within the tube and having a stem directed through the boss, the boss being split to provide contractible sections and means for contracting the sections to bind the same upon the piston stem to render the piston immovable. 95

3. In a whistle, a whistle base, a standard projecting upwardly therefrom, a bell vertically adjustable upon the standard and including a plurality of circularly arranged bell tubes, a piston within each bell tube, means for locking the pistons in adjusted 105 positions including a stem for each piston, a guide carried by each tube and through which the stem projects, said guide being compressible to clamp the stem and means for compressing the guide. 110

4. In a whistle, a whistle base, a standard extending upwardly therefrom, a sleeve supported from the standard, the bell including a structure having an axial bore surrounding the standard, said bore having threads for coaction with threads formed upon said sleeve and thereby affording means for vertically adjusting the bell upon the standard and a locking nut carried by the standard and abutting the bell to maintain the same 120 in adjusted positions. 115

5. In a whistle, a bell comprising a plurality of circularly arranged bell tubes, each having a piston adjustable therein, means for preventing rotation of the pistons, means for adjusting the pistons longitudinally of 130

the bell tubes and means for locking the pistons in adjusted position.

6. In a whistle, a whistle base, a standard extending upwardly therefrom, a bell vertically adjustable upon the standard, a piston adjustable in the bell, means for locking the bell in adjusted positions, means for locking the piston in adjusted positions, said piston being held against rotation with rela-

tion to the bell, a rotatably mounted stem ¹⁰ for the piston and having threaded engagement with the piston and means for locking the piston stem against rotation.

In testimony whereof we hereunto affix our signatures.

CHARLES CASH.
NICHOLAS E. WILSON.
